(57) **CLAIM**

The ornamental design for an in-vehicle navigation device, as shown and described.

DESCRIPTION

FIG. 1 is a front perspective view of an in-vehicle navigation device showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a front view under a powered condition having a stipple representing a color of illuminated graphic elements. The portions indicated in broken lines are for illustrative purposes only and form no part of the claimed design.
